UNITED STATES PATENT OFFICE

GUSTAV C. PEARSON, OF DENVER, COLORADO, ASSIGNOR TO GARDNER-DENVER COMPANY, OF DENVER, COLORADO, A CORPORATION OF DELAWARE

DRILL-STEEL BORE CONTRACTING MEANS

Application filed July 28, 1928. Serial No. 296,072.

The present invention relates to means for contracting the bores of drill steel and particularly those of the so-called "McLellan" type, in which the bit is provided with wings 5 formed by radially disposed cutting flanges. When a bit of this type is sharpened and the hole punched therein, it often occurs that the size of the hole or bore at the cutting end is so large that chips of rock broken 10 off by the cutting edges enter and clog the hole, thus making it impossible to feed a sufficient amount of water to the drilling face of the bit.

The object of the present invention is to 15 provide a novel structure of a simple and practical character for reducing the bore at the cutting end after the bit has passed through the sharpening process.

A further and important object is to provide a device of this character that can be 20 mounted on the front end of the ordinary hammer cylinder or barrel of a pneumatic tool.

In the accompanying drawings:

25 Figure 1 is a side elevation showing an assembled structure for the above purpose including a preferred embodiment of the invention.

Figure 2 is a detail longitudinal sectional view on an enlarged scale of the dolly mechanism.

Figure 3 is a front elevation of the same.

Figure 4 is a detail perspective view of the dolly and the associated holding pin.

35 Figure 5 is a longitudinal sectional view through a modified form of construction.

Figure 6 is a front elevation of the structure shown in Figure 5.

Considering first the embodiment disclosed in Figures 1-4 inclusive, a drill steel clamp is illustrated, comprising a pair of coacting jaws 7 and 8 that may be of any well known type and are designed to secure a drill steel 9. In line with these jaws is a 45 pneumatic tool which may be of any well known or desired construction, and in the form shown involves a cylinder member mounted on a base 10. This cylinder member includes a barrel 11, having a piston chamber 12 and provided with an enlarged

bore 13 in advance of said chamber. In the chamber is a reciprocating hammer piston 14 actuated by motive fluid that is distributed thereto in any well known manner.

In the rear end of the counter-bore 13 is 55 fitted a head disk 15, and abutting said head disk and fitted also into the chamber 13 in advance thereof, is a bushing 16. This bushing has an outstanding annular flange 17 located in advance of the barrel 11 and 60 secured thereto by cap screws 18 that pass through said flange 17 and are threaded as shown at 19 into the adjacent end of the barrel. Preferably interposed between the heads of the cap screws 18 and the flange 17 65 is a metal bearing disk 20 and a yielding washer 21 of cork or other suitable composition that absorbs some of the shock of the tool when in operation. The bushing 16 extends beyond the flange to form a chambered 70 casing 22 having a front end wall 23 provided with a central opening 24.

A reciprocating tappet 25 is located in the bushing 16 and chamber of the casing 22, and is provided with an external annular flange 26 operating in a chamber 27 formed in the rear end of the bushing 16. The rear and slightly reduced end 28 of the tappet extends through the head disk 15 into a position to be struck by the piston 29 hammer 14, as indicated in Figure 2. The front end of the tappet is provided with a central longitudinal bore 29, and into said bore is detachably fitted the stem 30 of a dolly. This dolly has an enlarged head 31 80 that operates in the central opening 24 of the front wall 23 of the casing 22. The dolly is held to the tappet preferably by means of a cross pin 32 that extends through a transverse opening 33 formed in the tappet and engaging in a notch 34 formed in the stem 30 of the dolly. This cross pin 32 preferably extends through and beyond the sides 85 of the casing 22, said casing having longitudinal slots 35 to receive the pin and permit its movement upon the reciprocation of the tappet.

The front or projecting end of the dolly head 31 is cupped as illustrated at 36, producing a circular cutting edge 37, said head 100

in effect acting as a die. It will also be noted particularly by reference to Figure 3 that the outer face of the front wall 23 of the casing 22 is provided with tapered 5 grooves 38 that radiate from the front end of the dolly head 31, these grooves being shaped to receive and interfit with the radial cutting flanges 39 of the bit 40 of the drill steel 9.

10 The operation of the structure is as follows: When a steel has been properly sharpened and the bore thereof opened, it is clamped by the jaws 7-8, with its cutting edges or flanges 39 engaged in the grooves 38. Obviously this centers the bit 40 and the bore 41 with respect to the dolly head 31, and incidentally acts as a firm abutment for the casing 22, and consequently for the entire pneumatic tool. If now the hammer 15 piston 14 is put in operation, it will deliver rapidly repeated blows to the tappet 25 and these blows will be transmitted to the dolly head, thus driving the front end thereof into the bit 40 and causing the metal 20 around the bore to be forced inwardly, contracting the discharge end of the bore as 25 will be clear by reference to Figure 2.

It will be clear that this structure is an exceedingly simple one that can be mounted 30 directly upon and in the end of an ordinary cylinder member or pneumatic hammer barrel, and that it will effectively perform the function of contracting the bore of the steel. More than that, it will be obvious 35 that by using the grooves 38 to center the bit of the steel, this centering action is made very accurate and steels with bits of different cross sectional areas will all fit to the same.

40 In Figures 5 and 6 a slightly modified form of structure is shown. Therein the barrel is designated 42, and the piston hammer is shown at 43. The rear head disk fitted into the barrel is designated 44 and the bushing cooperating therewith is illustrated at 45. In the present structure the chambered casing is shown at 46 and is a separate element from the bushing 45, being formed of sections, the joint being 45 shown at 47 held thereto by a retaining sleeve 48 bolted to the flange 49 of the bushing 45 by cap screws 50 that pass through a flange 51 formed on the retaining sleeve 48 through the flange 49 and being threaded into the front end of the barrel 42, as shown at 52. A shock-absorbing washer 53 is preferably interposed between the flanges 49 and 51. The chambered casing 46 is provided with an annular outstanding flange 54 and the retaining sleeve 48 has an inturned flange 55 located in advance of the flange 54. The casing 46 is capable of a limited reciprocatory movement in the retaining sleeve 48, and is normally pressed 50 outwardly by a coiled spring 56 surround-

ing the rear end of the casing 46 and abutting the rear side of the flange 54.

This casing 46 is provided with a front end wall 57 having a central opening 58. In the outer face of said wall 57, are radial grooves 59 that receive the cutting flanges of the steel bit. Operating in the bushing 45 and casing 46 is the tappet 60 adapted to be struck by the piston hammer 43 and carrying at its front end a dolly 61 through the medium of the stem 62, said dolly fitting into a socket 63 formed in the front end of the tappet. The dolly has its front end cupped, as shown at 64.

With this structure, the steel is placed 80 with its cutting flanges in the grooves 59 and the casing is pressed rearwardly against the action of the spring 56 so as to bring the die end of the dolly against the steel. The hammering action of the piston on the 85 tappet is transmitted to the dolly and contracts the discharge end of the bore of the steel by insetting the metal around the same in a manner already described.

From the foregoing, it is thought that the 90 construction, operation and many advantages of the herein described invention will be apparent to those skilled in the art without further description and it will be understood that various changes in the size, 95 shape, proportion and minor details of construction may be resorted to without departing from the spirit or sacrificing any of the advantages of the invention.

What I claim is:

1. In a structure of the character set forth, the combination with a chambered casing, the chamber of said casing having a front wall provided with an opening of less diameter than the chamber, of a tappet 100 slideable in the chamber of the casing, a dolly of less cross sectional area than the tappet 105 carried by the front end of the tappet and extending through the opening in the front wall of the chamber, said dolly having its 110 front end formed to inset the metal about the bore of a drill steel bit, and means carried by the exposed side of said front wall for centering the drill steel bit with respect to the dolly.

2. In a structure of the character set forth, the combination with a chambered casing having inset front wall forming a front wall for the chamber and having an opening of less diameter than the chamber, 120 of a tappet slideable in the chamber of the casing, a separate dolly of smaller diameter than the tappet projecting from its front end and extending through the opening in the front wall of the chamber, said dolly 125 having its front end formed to inset the metal about the bore of a drill steel bit, and means carried by said inset front wall for centering the drill steel bit with respect to the dolly.

3. The combination with a cylinder member including a barrel, of a bushing in the barrel, a chambered casing in front of the bushing and having a front end wall, a piston in the barrel, a tappet in the bushing having its rear end in position to be struck by the hammer and having its front end in the chamber of the casing, a dolly fixed in the front end of the tappet and having a front end that operates through the front end wall of the casing and is provided with a die formation to contract the metal of a steel bit about the bore of the steel, and bit flange-receiving grooves in the front end wall and radiating from the dolly to center a steel bit with respect to said dolly.
